FLOWERPOT HOLDER

Ronald C. Gempel, 1246 Folsom St.,
San Francisco, Calif. 94114

Filed Oct. 15, 1973, Ser. No. 406,599

Term of patent 7 years

Int. Cl. D11—02

U.S. Cl. D6—113

FIG. 2

FIG. 3

FIG. 1

FIG. 6

FIG. 5

FIG. 4

FIG. 7

FIG. 1 is a perspective view of a flowerpot holder showing my new design.

FIG. 2 is a front elevational view thereof.

FIG. 3 is a side elevational view thereof with the ring omitted for ease of illustration.

FIG. 4 is a back elevational view thereof with the ring omitted for ease of illustration.

FIG. 5 is a side elevational view thereof, showing the side opposite that shown in FIG. 3.

FIG. 6 is a top plan view thereof with the ring omitted for ease of illustration.

FIG. 7 is a bottom plan view thereof.

I claim:

The ornamental design for a flowerpot holder, as shown and described.
